WATER CAN

Robert V. Tompkins, Wyncote, Pa.

Application January 28, 1949, Serial No. 540

Term of patent 3½ years

(Cl. D58—17)

To all whom it may concern:

Be it known that I, Robert V. Tompkins, a citizen of the United States, residing at Washington Lane, Wyncote, in the county of Montgomery and State of Pennsylvania, have invented a new, original, and ornamental Design for a Water Can, of which the following is a specification, reference being had to the accompanying drawing, forming part hereof.

The single figure of the drawing is a perspective view of a water can, showing my new design.

I claim:

The ornamental design for a water can, substantially as shown.

ROBERT V. TOMPKINS.
